UNITED STATES PATENT OFFICE.

PAUL LOVECZKY, OF BROOKLYN, NEW YORK.

AEROPLANE.

1,276,778.

Specification of Letters Patent. Patented Aug. 27, 1918.

Application filed March 13, 1918. Serial No. 222,088.

To all whom it may concern:

Be it known that I, PAUL LOVECZKY, a citizen of the United States, residing at Brooklyn, county of Kings, and State of New York, have invented certain new and useful Improvements in Aeroplanes, of which the following is a specification.

This invention relates to improvements in aeroplanes and particularly to types driven by twin propellers arranged at the front of the apparatus.

The principal object of the invention is to provide means whereby the aeroplane may be safely and conveniently maneuvered, a plurality of motors being provided so that in case of the failure of one, the others may act.

A further object is to provide an aeroplane which may be deflected laterally or vertically in an easy and expeditious manner, and in which the motive power is under complete control.

A still further object is to provide an aeroplane which may be used to convey rapid fire or other guns, the apparatus having sufficient capacity to carry several people.

These and other like objects are attained by the novel construction and combination of parts hereinafter described and shown in the accompanying drawings, forming a material part of this disclosure, and in which:—

Figure 1 is a front elevational view of an aeroplane made in accordance with the invention.

Fig. 2 is a top plan view of the same.

Fig. 3 is a side elevational view thereof.

Fig. 4 is a fragmentary front elevational view.

Fig. 5 is a partial side elevational and sectional view, showing a preferred form of gun mount.

Fig. 6 is an enlarged sectional and side elevational view of the clutch, the section being taken on line 6—6 of Fig. 2, and

Fig. 7 is a fragmentary sectional view taken through the operator's seat and control means.

The apparatus is supported upon three wheels, two of which, indicated by the number 10, are arranged at the front upon an axle 11, while the third or rear wheel 12 rotates upon a spindle secured in the brackets 14, similar front brackets 15, supporting the axle 11, all of the several brackets being rigidly engaged below the platform 18.

Seats for the several operators, together

with the necessary standing room, is provided for in the downward extending well casings 19 and 20, arranged laterally of the platform, while a central depressed casing 21 or well 22 is provided in the platform at the extreme front thereof, for the person in control of the apparatus.

Standards 25 rise to a considerable height over the platform 18, and supported by the standards is the curved plane 26, while engaged between the plane and the platform, by the standards 25, is a rearwardly extending frame 28, all of the superstructures being connected by suitable guy rods 30 in the usual manner.

A vertical spindle 32 is mounted between the platform 18 and frame 28, the same having rigidly engaged upon it a rudder 33, by means of which the apparatus may be steered laterally as to the right or left.

Engaged at the upper end of the spindle 32, are extending lateral arms 34, to which are connected cords 35, the same running over pulleys 36 and 37, the ends of the cords being eventually attached to an eye 38, fixed in an angularly disposed spindle 39, arranged to be rotated by a hand wheel 40, the spindle being mounted in bearings 41, and 42, secured in the operator's well 22.

Also mounted above the platform 18 at the rear, upon spindles 45, journaled in brackets 46, is one of the horizontal rudders 48, a similar front rudder 49, being journaled on spindles 50, mounted in brackets 51, carried upon extending arms 52, rigidly attached to the platform 18, but extending forward to a distance.

Secured upon the spindles 45 and 50, are vertical rods 54 and 55 to which are secured cables 56 and 57, engaged by connections 58, from which extend other cables 60, the latter running over pulleys 61, and thence over pulleys 62, beyond which the ends of the cables are connected at points 58' and 57' on a lever 63, pivoted on a pin 64, projecting outward from a bracket 67, secured within the well 22, the lever being provided with an operating handle 68, and as one of the cables is connected below and the other above the pivotal point, it will be noticed that as the handle 68 is actuated, the planes or rudders 48 and 49 are moved in unison in the same direction upon their horizontal pivots. Thus by the control lever 69 both of the vertically operating levers may be readily operated.

Extending outwardly toward the front upon either side of the front rudder 49 are a pair of propellers 65 and 65' mounted upon shafts 66, journaled upon brackets 67, affixed upon the frame 28, while on the platform 18 are motors 70, 70', and 70'' the same being secured in parallel, the center motor 70' operating a shaft 72 direct, and attached upon the shaft 72 are sprockets 73 and 74, over which run chains 75 and 76, from the laterally disposed motors, so that the power of all three is concentrated upon the shaft 72.

The shaft 66 has secured upon it a sprocket 78, driven by a chain 79, upon the lower drive sprocket 80, on the shaft 72, other sprockets 83 and 84, on the shaft 66, communicating motion through the chains 85 and 86, to the propellers 65 and 65' when the shaft is rotated.

The shaft 66 is formed in two sections upon one of which, adjacent to the bracket 67, is rigidly engaged a positive clutch element 97, the mating clutch element 98 of which is slidable on the end of the other shaft section, the clutch elements being engageable through the forks 87 of a lever having a downwardly extending handle 88, convenient of access by an operator within the well 22.

Thus it is possible to connect or disconnect the sections of the shaft instantaneously at any desired time.

Secured in the lower portion of the wells 19 and 20, which are circular in cross-section, are standards 90, having upper portions 91, mounted on the lower part by annular ball bearings 92, the bearing being covered by annular casings 93, and engaged with the uppermost portion of the element 91, in such manner as to operate on a horizontal axis, is a lug 94, formed with a gun 95. This mounting permits the gun to be elevated or depressed with relation to its muzzle or to be rotated in any direction.

Also in addition to the well 20, is an extension 100, having an opening 101, so that bombs or the like may be dropped directly through the flooring of the well by an operator stationed therein. It being understood that an operator will also be stationed

near each of the guns, besides the person having general control of the apparatus within the well 22.

From the foregoing it will be readily seen that the device can be maneuvered in any direction and raised or lowered or to land, and that the propellers, together with the various directions control means, are conveniently actuated by a single operator.

Having thus described my invention what I claim as new and desire to secure by Letters Patent is:

1. In an aeroplane, the combination with a wheeled platform, a plurality of motors on said platform, driving connections engaging between said motors, a horizontal shaft mounted above said motors centrally thereof, driving connections between said motors and said horizontal shaft, a pair of twin propellers arranged parallel to said shaft, said shaft being in sections, clutch elements arranged upon each section of said shaft, and means for operating said clutch elements whereby said propellers may be put in motion.

2. In an aeroplane, the combination with a platform, landing wheels upon which said platform is mounted, standards rising from said platform, a frame supported by said standards, a plane arranged in the uppermost parts of said standards, a plurality of motors carried on said platform, all of said motors acting upon a single central shaft, a second shaft arranged vertically above said central shaft, connections between said shafts, said second shaft being formed in sections, clutch connections between said sections, means for operating said clutch connections, a pair of propellers driven by said second shaft, said propellers being operated in the same directions, a single vertical rudder, operating means for said vertical rudder, horizontal rudders arranged at the front and rear of said platform, and means for operating said horizontal rudders in unison, all of said control means terminating centrally of said platform.

In testimony whereof I have affixed my signature.

PAUL LOVECZKY.
